UNITED STATES PATENT OFFICE.

FRANK ORANGE BROWN, OF BEVERLY, MASSACHUSETTS.

DESIGN FOR A HOLDBACK-CLIP FOR VEHICLE-SHAFTS.

SPECIFICATION forming part of Design No. 33,952, dated January 22, 1901.

Application filed November 28, 1900. Serial No. 38,059. Term of patent 7 years.

To all whom it may concern:

Be it known that I, FRANK ORANGE BROWN, a citizen of the United States, residing at Beverly, in the county of Essex and State of Massachusetts, have invented and produced a new and original Design for a Holdback-Clip for the Shafts of Vehicles, of which the following is a specification, reference being had to the accompanying drawings, forming a part thereof.

The invention is fully disclosed in the following specification, of which the accompanying drawings form a part, in which—

Figure 1 is a front view of a holdback-clip, showing my new design; and Fig. 2, a plan view thereof.

As shown in the drawings, the leading or material feature of my design consists of a ring A, open at the bottom and provided with

projecting jaws B, and the ring A is provided on one side thereof (the right hand as viewed from the front) with a transverse arm D, the front end of which is provided with an outwardly and forwardly directed angular hook or extension E.

Having fully described my invention, what I claim as new, and desire to secure by Letters Patent, is—

The design for a holdback-clip, for the shafts of vehicles, as herein shown and described.

In testimony that I claim the foregoing as my invention I have signed my name, in presence of the subscribing witnesses, this 22d day of November, 1900.

FRANK ORANGE BROWN.
